(57) **CLAIM**

The ornamental design of an attachment for an electrical cable, substantially as shown and described.

DESCRIPTION

FIG. 1 is a top rear perspective view of a first embodiment of an attachment for an electrical cable;

FIG. 2 is a top front perspective view of the attachment in FIG. 1;

FIG. 3 is a top view thereof;

FIG. 4 is bottom view thereof;

FIG. 5 is a front view thereof;

FIG. 6 is a rear view thereof;

FIG. 7 is a left side view thereof;

FIG. 8 is a right side view thereof;

FIG. 9 is a top rear perspective view of a second embodiment of an attachment for an electrical cable;

FIG. 10 is a top front perspective view of the attachment in FIG. 9;

FIG. 11 is a top view thereof;

FIG. 12 is bottom view thereof;

FIG. 13 is a front view thereof;

FIG. 14 is a rear view thereof;

FIG. 15 is a left side view thereof; and,

FIG. 16 is a right side view thereof.

The dash-dash-dash-dash broken lines shown in the drawing views are included for the purpose of illustrating portions of the attachment for an electrical cable that form no part of the claimed design. The dash-dot-dash-dot broken lines shown in the drawing views define the boundary of the claimed design.
